HYDRAULIC VALVE LIFTER

Kenneth D. Jackson, Utica, N. Y.

Application June 5, 1935, Serial No. 25,163

2 Claims. (Cl. 29—86.3)

This invention appertains to new and useful improvements in valve lifters for conveniently lifting the valves of the type generally employed in internal combustion engines.

5 The principal object of the present invention is to provide a hydraulic valve lifter which will eliminate a considerable amount of the manual exertion necessary in compressing the valve spring.

10 Other important objects and advantages of the invention will become apparent to the reader of the following specification.

In the drawings:

Figure 1 represents a perspective view of the 15 lifter.

Figure 2 represents a rear elevational view of the spreader.

Figure 3 represents a longitudinal sectional view through the lifter.

20 Figure 4 represents a fragmentary top plan view of the yoke ends of the upper pair of arms.

Referring to the drawings wherein like numerals designate like parts it can be seen that the numeral 5 represents a block construction 25 provided with a removable hollow cylindrical extension 6 forming a handle. The bottom of this hollow handle 6 can be opened to permit the handle to be filled with oil or like substance by removing the plug 7.

30 Extending forwardly from the body 5 is the cylinder 8 in which the plunger 9 is slidable. The forward edge of this cylinder 8 is provided with a removable threaded bushing 10 through which the connecting rod 11 of the plunger 9 is 35 slidable. Secured by a screw or like means 12 at the outer end of the rod 11 is the cross bar 13 serving as a spreader for the upper and lower pair of arms, this spreader 13 being slotted at its upper and lower ends as at 14. Springs 14a

40 serve to prevent rattling of the arms. The upper pair of arms consist of two elongated bars being bent at the inner portion to describe a substantially L-formation a—b while the forward end portion is diverged upwardly slightly as at c 45 where it ends at a semi-circular half-yoke d having an upstanding flange e at its outer edge. The yoke end of these arms are adjustably connected together by a screw 15.

An ear 16 on the top portion of the body 5 has 50 the inner end of the upper pair of arms pivotally secured thereto by suitable members 17. The lower arms are similarly formed at their inner portions to follow a general L-formation a'—b' and these arms at their inner ends are pivotally 55 secured to opposite sides of the block 5 as at 16.

These arms extend through the lower yoke 14 of the spreader 13 and have straight extending portions 17 at their outer ends adjustably connected together by a screw 18 and which underlies the yoke portion d.

5 A coiled compressible spring 19 is convoluted on the connecting rod 11 and interposed between the plunger 9 and the bushing 10, thus maintaining the plunger 9 in retracted position with the ends 17 of the arms and the yoke portion d of the upper arms in the contracted relation shown in Figure 3.

A threaded bore 20 receives the threaded valve shell 21 which has a portion communicating with the duct 22 leading to the hollow handle tank 15 and another port registering with the duct 23 which extends upwardly from the cylinder 24. A valve element 25 can be threaded into the shell 21 to either close or communicate the duct 23 with the duct 22. A branch duct from the duct 20 23 communicates with the cylinder 8 as at 26 and another branch duct 27 extends from the duct 23 to the hollow handle 6 and has a check valve 28 therein. An additional check valve 29 is provided between the branch duct 26 and the duct 23. 25

Operative in the cylinder 24 is a plunger 30 which is slidable through the packing gland 31 at the lower end thereof. A depending post 32 on the body 5 extends into the bifurcated edge portion 33 of the lever 34 and a pin 35 pivotally connects the handle at this point to the post 32 while a link connection 36 is established between the bifurcated end of the lever 34 and the said plunger 30.

35 It can now be seen, that normally a volume of oil is in the cylinder 24 and when the lever 34 is moved upwardly the plunger 30 forces the contents of the cylinder 24 upwardly through the duct 23, passing check valve 29 and into the chamber 8 where it exerts a stop against the plunger 9 and forces the spreader 13 outwardly to separate the yoke d of the upper arm and the extension 17 of the lower arm.

40 Obviously when the handle 34 is released, the spring 19 will return the plunger 9 driving the fluid back through the valve shell 21. Of course the valve 25 must be open or otherwise the arms will be maintained in separated position. This valve 25 serves as a lock for the fluid until it is opened and then it returns to the handle 6 and 50 then from the handle 6 back to the check valve 28 to the cylinder 24. This latter operation generally takes place when the handle 34 is first moved downwardly to fill the chamber 24 with fluid.

While the foregoing specification sets forth the invention in specific terms, it is to be understood that numerous changes in the shape, size and materials may be resorted to without departing from the spirit and scope of the invention claimed hereinafter.

Having thus described the invention, what is claimed as new is:

1. A valve lifter comprising a hollow handle 10 for containing a fluid, a cylinder extending from the said hollow handle and a passageway between the hollow handle and the cylinder provided with a valve therein, a plunger in the said cylinder, an upper and lower pair of valve spring 15 engaging arms, a spreader carried by the said plunger for spreading the said arms apart when the spreader is extended, and manual means for

driving fluid into the cylinder for extending the said plunger.

2. A valve lifter comprising a hollow handle for containing a fluid, a cylinder extending from the said hollow handle and a passageway between the hollow handle and the cylinder provided with a valve therein, a plunger in the said cylinder, an upper and lower pair of valve spring 10 engaging arms, a spreader carried by the said plunger for spreading the said arms apart when the spreader is extended, manual means for driving fluid into the cylinder for extending the said plunger, and a check valve between said cylinder and manual means so as to hold the arms in extended position until the first mentioned valve 15 is moved to open position.

KENNETH D. JACKSON.
